[57] CLAIM

The ornamental design for a lensmeter, as shown and described.

DESCRIPTION

FIG. 1 is a top, front, right side perspective view of a lensmeter showing our new design;

FIG. 2 is a right side elevational view thereof, the left side being a mirror image of that shown;

FIG. 3 is a front elevational view thereof; and,

FIG. 4 is a top plan view thereof.

The bottom and rear of said lensmeter are merely plain and include no ornamentality.
